J. E. PEARSON

OIL BURNER

Filed Nov. 18, 1921

INVENTOR
J. E. Pearson
BY *Maurice R. Stoe*
ATTORNEYS

UNITED STATES PATENT OFFICE.

JOHN E. PEARSON, OF CHICAGO, ILLINOIS.

OIL BURNER.

Application filed November 18, 1921. Serial No. 516,089.

To all whom it may concern:

Be it known that I, JOHN E. PEARSON, a citizen of the United States, and a resident of Chicago, in the county of Cook and State 5 of Illinois, have invented a new and useful Improvement in Oil Burners, of which the following is a full, clear, and exact description.

My invention relates to improvements in 10 oil burners, and more particularly to that type of oil burner which is adapted to heat a furnace, and it consists in the combinations, constructions, and arrangements herein described and claimed.

15 An object of my invention is to provide an oil burner which operates noiselessly.

A further object of my invention is to provide a device of the type described which has an automatic valve of novel construction.

20 A further object of my invention is to provide a device of the type described which has a burner of novel construction.

A further object of my invention is to provide a device of the type described which 25 is simple in construction, consists of few moving parts, and is not likely to easily get out of order.

Other objects and advantages will appear 30 in the following specification, and the novel features of the invention will be particularly pointed out in the appended claims.

My invention is illustrated in the accompanying drawings, forming part of this application, in which—

35 Figure 1 is a side elevation of the device, portions thereof being shown in section,

Figure 2 is an end elevation of the device, portions thereof being shown in section, and

40 Figure 3 is an enlarged sectional view of the oil burner.

In carrying out my invention, I provide a stand or support 1 which has a pedestal 2 integral therewith. On the pedestal 2 I 45 mount a fan 3 which is preferably of the centrifugal type. The fan 3 is connected by means of a coupling 4 to a valve 5, which will now be described.

The valve 5 comprises a body portion 6 which has a bore 7 adapted to communicate with the fan 3 and a bore 8 which extends at right angles to the bore 7. Slidably disposed in the bore 8 is a valve 9 which has a stem 10 integral therewith, the stem projecting above the body portion 5.

As will be noted in Figure 1, the valve 9 has a tapered upper portion which is adapted to close the bore 8. The upper end of the stem 10 is connected with a solenoid 11 by means of a bell crank lever 12 and a link 13 for a purpose hereafter described. Disposed adjacent the outer end of the bore 7 is a gravity controlled cover 14. An oil inlet chamber 15 is secured to the body portion 5 and is provided with a passage 16 60 communicating with the bore 8 and with a passage 17 connected with a source of oil supply by means of a pipe 18. The passages 16 and 18 communicate with each other and the passage 18 is restricted adjacent to 70 the passage 16, and a needle valve 19 is adapted to shut off the oil supply from the passage 17. A spring 20 is disposed in the bore 8 and bears on the under side of the valve 9. An electric motor 21 is operatively 75 connected to the fan 3.

A burner 22 is connected to the fan 3 by means of a pipe 23. The burner is provided with a casing 24 which is disposed concentrically with respect to an adjustable air 80 pipe 25. As will be noted in Figure 3, the end of the air pipe 25 is adapted to close the opening 26 of the casing 24 so as to prevent the oil which flows from the pipe 23 from passing through the opening. The 85 pipe 25 is provided with an annular groove 27 adjacent the outer end thereof which can be moved into alignment with the opening 26 and thereby permit the oil in the casing 24 to pass through the opening. The 90 groove 27 is curved so it will spray the oil as it passes through the opening 26.

From the foregoing description of the various parts of the device, the operation thereof may be readily understood. I place 95 the support 1 in any convenient place which is adjacent to the furnace (not shown) and dispose the burner 22 in the combustion chamber of the furnace. I then regulate the valve 19 by means of a handle 28 so that 100 the oil in passing from the passage 17 into the passage 16 is sprayed by the valve 19. When the device is desired to be operated, the electric motor 21 is started and the solenoid 11, which is in series therewith, is 105 actuated so as to move the valve 9 downwardly against the tension of the spring 20 and to open the bore 8. The fan 3, which is now rotated by the motor 21, draws the oil from the pipe 18 through the passage 110

17, the needle valve 19, the passage 16, the bore 8, and forces it on through the pipe 23. As heretofore stated, the oil passing through the pipe 23 is in sort of a mist, 5 since it has been effectively broken up by the needle valve 19. The oil passing through the pipe 23 is also provided with the desired amount of air, since the suction created by the fan 3 raises the cover 14 10 and permits air to enter the bore 7 and to mix with the oil. The oil, which is now in the form of a spray and which is also mixed with the proper amount of air, enters the casing 24 and passes through the opening 26 thereof. The groove 27 further aids in spraying the oil as it passes from the opening 26 and regulates the quantity of oil passing from the opening. An additional amount of air is also provided to the combustion chamber of the furnace by means 20 of the pipe 25 and therefore complete combustion of the oil in the furnace is assured.

The operation of the device can be instantly stopped by merely cutting off the supply 25 of electricity to the motor 21. As soon as this is done, the solenoid 11 becomes de-energized and permits the spring 20 to instantly seat the valve 9. It will therefore be seen that the oil from the pipe 18 is in- 30stantly checked and is prevented from entering the bore 7 or the upper portion of the bore 8. The suction of the fan 3, which continues to operate a certain length of time after the source of current has been shut off from the motor, will now draw air 35 through the bore 7 and will be prevented from drawing oil into the fan 3, since the valve 9 has instantly cut off the supply of oil. The oil is therefore prevented from 40 entering the fan 3 and will not become sluggish therein while the fan 3 is idle. When the device is again started, the fan 3 will not be hindered from rotation, since there is no oil therein.

I claim:

1. A device of the type described comprising a valve connected with a source of fluid supply, a spring normally adapted to seat said valve, a suction fan connected with said valve, a burner connected with 50 said fan, said fan forming a part of the oil passageway between said valve and burner, means for actuating said suction fan, and means cooperating with said fan operating means for automatically opening said valve 55 when said fan operating means is actuated.

2. A device of the type described comprising means connected with a source of fluid supply for spraying the fluid, an automatic valve connected with said means, a 60 suction fan connected with said valve, an air inlet disposed between said fan and said valve, means for actuating said fan, means for automatically opening said valve when said fan actuating means is operated, and a 65 burner connected with said fan, said fan forming a portion of the oil passageway between said valve and said burner.

3. A device of the type described comprising a fuel mixing chamber, a valve for 70 controlling the flow of fuel into said fuel mixing chamber, a fuel outlet nozzle, a fan for drawing the fuel from said mixing chamber and for forcing it to said nozzle, means for actuating said fan, and means co- 75 operating with said fan cooperating means for automatically opening said valve when said fan operating means is actuated.

4. In a device of the type described, a valve in communication with the source 80 of fuel supply, a suction fan in communica- 85 tion with said valve, means for operating said fan and means cooperating with said fan actuating means for opening said valve when said fan actuating means is started and for instantly closing said valve when said fan actuating means is stopped.

JOHN E. PEARSON.
